HERBERT T. ABRAMS, OF ORANGE, NEW JERSEY, ASSIGNOR TO INGERSOLL-RAND COMPANY, OF JERSEY CITY, NEW JERSEY, A CORPORATION OF NEW JERSEY.

AUTOMATIC VALVE FOR AIR LIFT-PUMPS.

1,343,190.

Specification of Letters Patent. Patented June 15, 1920.

Application filed March 27, 1919. Serial No. 285,433.

To all whom it may concern:

Be it known that I, HERBERT T. ABRAMS, a citizen of the United States, residing at Orange, in the county of Essex and State of New Jersey, have invented a certain new and useful Improvement in Automatic Valves for Air Lift-Pumps, of which the following is a specification.

This invention relates to air lift pumps in which water or other fluids and semi-fluids are pumped through an eduction pipe supplied with air under pressure acting directly on its submerged end.

The present invention specifically relates to a means for regulating the pressure and consequently the amount of air supplied to the submerged end of the eduction pipe of an air lift pump, the means provided permitting an increased pressure of air to be admitted to the eduction pipe when the back pressure in said eduction pipe due to the depth of submergence is increased and a lessened pressure when the back pressure is lowered.

In air lift pumps as at present constructed a regulating or throttling valve is provided in the air supply line which may be adjusted by hand to suit the conditions normally existing within the eduction pipe. These conditions vary intermittently due to released bubbles or pistons of air so that the supply of air cannot be properly regulated to maintain economical operation. Also, when several pumps of this type are operated by compressed air at the same pressure as when supplied from the same source, a pump in which the back pressure is lower than the others will take an unduly large amount of air, thus seriously affecting the economy of that particular pump and depriving the remaining units of sufficient air for efficient operation.

It is therefore an object of the present invention to provide an automatic means for regulating the pressure of air supplied to an eduction pipe of an air lift pump which will vary the pressure simultaneously with changes in operating conditions within the pump. Another object is to provide an automatic regulating valve which will be simple, positive in its action and will not readily be put out of order.

With these and other objects in view my invention consists in the features of con-

struction and operation set forth in the following specification and illustrated in the accompanying drawings, in which—

Figure 1 shows a cross sectional view of an air lift pump of conventional type equipped with an automatic regulating valve as above described.

Fig. 2 shows a cross sectional view in elevation of a valve made in accordance with the present invention.

It is to be understood that the form of air lift pump shown in Fig. 1 is merely for the purpose of illustration and the invention is in no way limited to any particular form of eduction pipe or air supply pipe, and also that the particular form of valve shown in Fig. 2 is illustrative only of an application of the invention which is in no way limited to any particular form of valve. In the pump as shown an eduction pipe is shown within the well casing but it is to be understood that a special eduction pipe is not required but that the well casing or similar part may perform all the functions of the eduction pipe. Referring more particularly to the figures of the drawing, 1 refers to a well casing forming the lining for an air lift pump in which is located an eduction pipe 2 extending considerably below the pumping line which is indicated by line 3—3. This form of an air lift pump is one commonly used for pumping water from depths of from two hundred to twelve hundred or more feet. Within the eduction pipe 2 is shown an air supply pipe 4 connected with a source of supply (not shown) by means of pipe 5. The air supply pipe 4 extends down to the lower or submerged end of the eduction pipe 2 and at that point is provided with a plurality of openings 6 forming nozzles through which air escapes into the eduction pipe 2 and, in ascending through the eduction pipe, carries with it a large amount of the water or other fluid within the well or other receptacle from which the fluid is being pumped. Inserted within the air supply line 4 at a convenient point above the level of the ground is an automatic regulating valve 7 which forms the subject matter of the present invention.

Referring now to Fig. 2 in which a regulating valve suitable for the above purpose is more clearly shown, the valve comprises a casing 8 into which is suitably secured the

air supply pipe 5 connected with any suitable source of compressed air and also the air supply pipe 4 leading to the submerged end of the pump. Within the casing 8 operates a piston 9 which in its movement upwardly and downwardly opens and closes a port 10 leading from the portion of the casing 8 directly below the piston in which the full pressure of air in pipe 5 is exerted 10 into the air supply pipe 4. The casing is provided with a suitable cap 11 to limit the upward movement of the piston 9. This cap 11 is also provided with a bracket 12 to which is pivoted by means of a pin 13 an 15 arm 14 which at its outer end may carry a heavy weight 15. The weight 15 riding on arm 14 may be shifted toward or away from the pivot 13 to increase or decrease the pressure on a connecting arm 16 which 20 at its upper end fits into a depression 17 and at its lower end presses against the piston 9. This construction just described provides a valve acted upon by pressure within pipe 5 and allows variable amounts 25 of air to pass from pipe 5 into the pipe 4 dependent upon the pressure within pipe 4. From this disclosure it will be seen that with the variations in the air pressure within air supply pipe 4 due to an increased or 30 decreased flow of air through the valve different pressures are exerted on the lower face of the piston 9 and that with the arm 14 suitably weighted by properly locating the weight 15, the valve formed by piston 35 9 and the port 10 may be made to close when the pressure against it is reduced below a critical pressure and that pressure above that critical pressure will hold the piston 9 in an intermediate position between 40 its closed position and wide open position as shown in Fig. 2. With a rapid flow of air past the valve, pressure below the piston 9 is reduced and piston moves downwardly slightly thus cutting off a part of port 10 45 and reducing the supply of air to the submerged end of the eduction pipe. When the difference in pressure between supply pipe 5 and the submerged end of the eduction pipe is reduced which condition occurs when 50 the back pressure due to submergence is increased, greater pressure is exerted below

piston 9 and consequently piston 9 moves upwardly thus more fully opening port 10.

In operating a series of pumps supplied from the same source of air pressure the 55 weight 15 on each valve provided on each of the pumps is adjusted so that the maximum flow of water will take place when in normal operation and under normal back pressure. As soon as the pressure within one of the 60 wells drops due to withdrawing the water or other liquid more rapidly from the well or other place from which the liquid is being pumped than it is being supplied, the piston 9 moves downwardly slightly to 65 partly close port 10. This has the desired effect of limiting the amount of air supplied to that particular pump and will not permit an increased flow of air through that particular pump until the pressure is restored 70 as would be the case if no automatic regulation were provided.

What I claim is:

In an air lift pump, a well casing, or lining, an eduction pipe extending from the 75 surface to a point near the bottom of the well, an air supply pipe extending to the lower submerged end within the eduction pipe and adapted to be connected with a source of supply of air pressure, and an au 80 tomatic regulating valve inserted in the air supply pipe at a point above ground for varying the air pressure in accordance with changes in back pressure in the eduction pipe, said valve comprising a valve casing 85 to which the air supply pipe and the source of supply are connected, a piston valve in said casing adapted to control a port leading to the air supply pipe and means for exerting pressure on said valve to oppose 90 the air pressure beneath the valve, whereby variations of the difference in pressure between the pipe leading to the source and the submerged end of the eduction pipe due to variations of back pressure in the well 95 causes the valve to vary the port leading to the air supply pipe to compensate for said variations of differences in pressure.

In testimony whereof, I have hereunto set my hand.

HERBERT T. ABRAMS.
